(57) **CLAIM**

The ornamental design for a controller portion, as shown and described.

DESCRIPTION

FIG. 1 is a front perspective view of a controller portion showing our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The black broken lines in the drawings depict unclaimed environmental structure of the controller, while the gray broken lines in the drawings depict unclaimed environmental surface indicia. All broken lines, and environment depicted by them, form no part of the claimed design.
